BOILER

Julius Krug, Berlin, Germany, assignor to Combustion Engineering Company, Inc., New York, N. Y.

Application September 19, 1935, Serial No. 41,206
In Germany September 28, 1934

9 Claims. (Cl. 122—235)

The present invention relates to steam generators and particularly to cooling screens for the walls of the furnaces thereof.

One object of the present invention is to improve the circulation in such boilers.

Another object is to obtain the maximum possible separation of water in the cooling screen about the furnace from the water circulations in other portions of the boiler.

10 A third object of the invention is to lessen the cost of the boiler.

In accordance with the invention, these objects are attained by providing for uniform distribution of steam and water and by providing risers from the upper header of the cooling screen that discharge above the water level in the boiler drum and in which the total loss of head, with substantially dry steam flowing therethrough, is substantially equal or about equal to the difference of the water head above the elevation of the inlet of the risers plus the rising force in the water walls on one hand minus the resistance of the downcomers to the walls plus the resistance to flow in the water walls themselves on the other hand.

By this arrangement the water within the cooling tubes is for the main part retained within the cooling screen so that substantially only steam flows through the riser tubes to the boiler drum, and substantially only enough water is fed to the screen to make up for the steam released. Thus, the boiler drum receives from the screen substantially only steam, so that steaming within a boiler having other generating tubes is not influenced by the cooling screen.

Consequently, a cooling screen constructed in accordance with the invention is particularly suited to boilers which deliver wet steam and whose furnaces are to be faced with cooling tubes, or whose capacity is to be raised by the use of furnace cooling screens in combination with an increase in the firing capacity. Likewise, it is possible by reconstructing existing cooling screens, in accordance with the teaching of this invention, to reduce the wetness of steam in a unit and/or to improve the operation of the boiler. In the drawings:

Figure 1 is a vertical sectional view of a boiler having a cooling screen for the furnace walls arranged in accordance with the invention;

Figures 2 and 3 are sectional views along the lines 2—2 and 3—3 in Figure 1;

Figure 4 is a view similar to Figure 1 but showing a lateral offtake for flue gases rather than a vertical one as in Fig. 1;

Figure 5 is a diagrammatic view illustrating the circulation within the cooling screen; and

Figure 6 is an enlarged view illustrating one manner of connecting the steam risers to the upper header of the cooling screen.

In the drawings the numeral 10 designates a furnace chamber the walls of which are cooled by water screens formed of tubes at least partly exposed to the radiant heat of the gases of combustion. The water screens along the front and back walls comprise riser tubes 11, 12 connected between a lower transversely disposed header drum 13 and an upper transverse header drum 14, these tubes also having portions 11a, 12a extending across the top and bottom respectively, of chamber 10. The side wall screen tubes 15 are connected into upper and lower headers 16, 17 that are disposed along the side walls. The headers 16, 17 are connected in turn to drums 14 and 13, respectively, by tubes 18, 20 intermediately bent at right angles and extending across and along the furnace chamber 10 above and below, respectively, the top tubes 11a and bottom tubes 12a. Recirculator tubes 21 extend from upper drum 14 to lower drum 13.

The lower drum 13 receives water from the boiler drum 22 through downcomers 23, those in the arrangement of Figure 5 connecting into the lower water drum 24 to which the generating tubes 25 and main downcomers 26 are connected; although the lower portions of tubes 21 extend across the furnace chamber, they function as recirculators since the vertical portions thereof which are connected to drum 14 are maintained cool by the furnace wall and the water head therein causes downward circulation in the direction of the arrows appearing in the drawings because the production of steam in these tubes can at most effect a slight reduction in the effective water head. The downcomers 23 and recirculators 21 are protected by the walls 27 or may be screened by the risers 11 and 12, respectively, as in Figure 4. The upper drum 14 of the water screen is connected to the boiler drum 22 at a level above the water line therein by risers 30.

As indicated in Fig. 5 the total loss of head R in the risers 30, with substantially dry steam flowing therethrough, is substantially equal or about equal to the difference of the water head P above the elevation of inlet of the risers plus the rising force in the water walls on one hand minus the resistance of the downcomers R₁ to the walls plus the resistance to flow in the water walls themselves on the other hand.

In accordance with the invention the risers 30 are carried downwardly into the steam release or upper header 14, as shown in Figure 6, and provided with slits or holes similar to well screens 5 (or the tubes may be cut off diagonally) whereby a greater projection of risers 30 into the header 14 exposes a greater steam release area. Thus, a water level is obtained in the steam release header 14 at such a height that resistance 10 through the exposed free areas of the outlet screen 29 and riser tubes 30 equals the pressure head P of the boiler water level above the steam release line in header 14.

When firing is started, the tubes 11, 12, 15 absorb heat from the fire and generate steam 15 which, mixed with water, ascends into risers 30. As the load increases, a water level will be established in drum 14 and only steam will flow into risers 30 through the basket screen 29 and in 20 time the remaining water is crowded out of the risers, so that eventually only steam flows through them. As a result, at higher loads the water is driven from the risers 30 and a water level maintained in the upper screen header 14 so that only 25 steam ascends from the screen tubes through risers 30 to the boiler drum 22.

The recirculators 21 return water from header 14 to header 13 and only sufficient water flows 30 from boiler drum 22 through downcomers 23 to replace that ascending as steam into the boiler drum through risers 30 upon being converted 35 into steam in the water screen. This results in the greatest possible separation of the water circulation in the water screen and in the remaining generating surfaces of the boiler. These circulations may be determined in advance and conflicting flows, as well as stagnation or reversal of flows with consequent overheating of the tube material is avoided. By obviating conflicting 40 flows the resistance to flow circulation is reduced so that circulation in existing boilers may be improved by installing a water screen in accordance with this invention, or for a given circulation the tube areas and/or number of tubes may be reduced, which in addition to cheapening the 45 cooling screen lessens the cost of the boiler.

At low loads and low steam generation the velocity and therewith the resistance within the risers 30 is lower. Consequently, water may be 50 discharged from the cooling screen into the boiler drum. Nevertheless, the arrangements of the present invention have the advantage that the higher the load the higher will be the steam delivered by the boiler and less water will be 55 carried into the drum 22 with the steam whereas usual boiler arrangements deliver relatively wet steam at maximum loads. Furthermore, variations in load have less influence on the cooling screens subjected to radiant heat than on the 60 convection parts of the boiler.

Parallel flow and uniform distribution of water and steam is attained in the entire tube system of the boiler due to the parallel disposition of the feed drum 22 and headers 13, 14 with respect to 65 each other and because of the connection of the tubes of the several groups into uniformly distributed openings arranged in longitudinal rows along the length of feed drum 22 and headers 13, 14. From the above it follows that in addition to the uniform expansion of the tube system and drums, markedly less resistance to the flow exists in the tube system, so that the circulation is either increased or, for the same circulation, 70 fewer downcomers may be used.

75 The risers 30 from the cooling screen are led to

the steam and water drum 22 within the flu gas offtake 32 and thus these tubes act as superheater elements and serve to dry the steam and partially superheat it before it arrives in drum 22.

Parallel flow and uniform distribution of feed water between drum 22 and lower header 13 and of steam between upper header 14 and drum 22 (which also serves as the steam drum) is assured by the connection of the downcomers 23 and risers 30 into longitudinal rows of uniformly 10 spaced openings in the header 13, 14 and drum 22. Likewise the connection of the wall tubes 11, 12, 15 into the headers 13, 14 results in uniform distribution and parallel flow through the cooling screen. The tubes of various groups of 15 the cooling screen are of nearly the same length so that their portions exposed to the flame absorb substantially the same amount of heat and consequently develop the same velocity of flow.

The uniform distribution of the recirculator tubes 21 connecting the upper header 14 with the lower header 13 eliminates longitudinal flow of 20 water in header 14 that would offer resistance to the rising currents of steam and water from the wall tubes 11, 12 and 15. The connection of the 25 side wall tubes 15 and recirculator tubes 21 into longitudinal rows of openings in header 14 also prevents mutual interference between the flow of the water and steam mixture rising from tubes 11, 12, 15 and the flow of water separated from 30 steam in header 14 and returned to drum 13, as has heretofore been the case in other boilers in which steam from side wall tubes entered the end of a steam and water drum and the water recirculated through tubes connecting near the end 35 of the drum.

Further, the feed water drum 22 serves directly as a header for the superheater 33 as well as for the feed water heater tube system 34, so that a parallel flow is also maintained in these tubes, 40 and it is only necessary to have one header 35 for leading off the superheated steam and one header 36 for delivering the feed water to the tube system. The parallel connection of the economizer and superheater tubes to drum 22 assures uniform 45 intensity of flow of water from the economizer into the steam generator as well as of steam to the superheater so that cross flows and resistances in drum 22 are kept to a minimum.

Feed drum 22, as well as upper header drum 14, 50 and the side wall upper headers 16, are supported by the boiler framing 29. The lower drum 13 hangs from tubes 23, which in turn hang from drum 22. The furnace riser tubes 11, 12, 15 are in this way relieved of the weight of the lower 55 drum and are consequently subject only to the strains which result from heating them. They are thus free from weight strains so that all the risers may expand uniformly.

Incidentally, a boiler embodying the features of 60 the invention may be constructed very cheaply and with a small number of hand hole closures and with greater operating safety since only three drums and two headers are required; one drum serving simultaneously as a steam separator and 65 accumulator and as a header for the superheater and economizer; the other two drums serving to distribute water to the cooling screen and to collect steam therefrom. It may be noted that the cooling tubes along the several walls of the furnace are connected into a common upper drum 14 whereby greater quantities of steam are gathered 70 into the one drum and whereby a more uniform distribution of the risers 30 longitudinally of the 75

header as well as along the drum 22 may be obtained.

What I claim is:

5. 1. In a boiler having a furnace chamber; a cooling screen for two opposite walls of the latter comprising a header disposed along the bottom of one wall; a second header disposed along the top of the other wall; circulating tubes covering the said walls of said chamber connected into uniformly spaced openings disposed longitudinally of said headers and having portions extending over the roof and floor of said chamber; a steam and water drum disposed parallel to and above said first mentioned header; downcomers connecting into uniformly spaced openings disposed longitudinally of said drum and first mentioned header; and riser tubes connecting into uniformly spaced openings disposed longitudinally of said other header and said drum.
10. 2. In a boiler having a furnace chamber; a cooling screen for two opposite walls of the latter comprising a water feeding header disposed along the bottom of one wall; a steam collecting header disposed along the top of the other wall; circulating tubes covering the said walls of said chamber connected into uniformly spaced openings disposed longitudinally of said headers and having portions extending over the roof and floor of said chamber; a steam and water drum disposed parallel to and above said first mentioned header; downcomers connecting into uniformly spaced openings disposed longitudinally of said drum and first mentioned header; and riser tubes connecting said steam collecting header to said steam and water drum, said tubes being disposed in the path of gases from said chamber and serving as superheater tubes for steam passing from said header to said drum.
15. 3. In a boiler having a furnace chamber; a cooling screen for the walls of the latter comprising, a lower header disposed along the bottom of one wall; an upper header disposed along the top of the opposite wall; circulating tubes covering the front and back walls of said chamber connected into uniformly spaced openings disposed longitudinally of said headers and having portions extending over the roof and floor of said chamber; a steam and water drum disposed parallel to and above said lower header; downcomers connecting into uniformly spaced openings disposed longitudinally of said drum and lower header; circulating tubes covering the opposite side walls of said chamber; uniformly spaced circulators connected with said side wall tubes and extending across and along the top and bottom, respectively, of said chamber to said upper and lower headers, respectively; and risers common to all said walls connecting said upper header to said steam and water drum.
20. 4. In a boiler having a furnace chamber; a cooling screen for opposite walls of the latter comprising a header disposed along the bottom of one wall; a second header disposed along the top of the other wall; circulating tubes covering the said walls of said chamber connected into uniformly spaced openings disposed longitudinally of said headers and having portions extending over the roof and floor of said chamber; a steam and water drum disposed parallel to and above said first mentioned header; downcomers connecting into uniformly spaced openings disposed longitudinally of said drum and first mentioned header; and a superheater and an economizer having one end of each heat absorbing element thereof directly connected into uniformly spaced

openings disposed longitudinally of said steam and water drum.

5. In a boiler having a frame; a steam and water drum supported thereon; a furnace chamber; water circulating tubes covering one pair of opposite walls thereof and having portions extending over the roof and floor of said chamber; an upper header supported in the frame to which said tubes are connected at one end; a lower header to which said tubes are connected at the opposite end; downcomers connected between said drum and lower header and supporting the latter; and riser tubes connecting said upper header to said drum.

6. In a boiler having a frame; a steam and water drum supported thereon; a furnace chamber; water circulating tubes covering one pair of opposite walls thereof and having portions extending over the roof and floor of said chamber; an upper header supported in the frame to which said tubes are connected at one end; a lower header to which said tubes are connected at the opposite end; downcomers connected between said drum and lower header and supporting the latter; riser tubes connecting said upper header to said drum; and tubes covering the side walls of said chamber and connected into upper headers supported in the frame and lower headers adjacent the bottom of said chamber.

7. In a boiler having a frame; a steam and water drum supported thereon; a furnace chamber; water circulating tubes covering the front and back walls thereof and having portions extending over the roof and floor of said chamber; an upper header supported in the frame to which said tubes are connected at one end; a lower header to which said tubes are connected at the opposite end; downcomers connected between said drum and lower header and supporting the latter; riser tubes connecting said upper header to said drum; tubes covering the side walls of said chamber and connected into upper headers supported in the frame and lower headers adjacent the bottom of said chamber; and bent tubes covering the top and bottom of said chamber and connected between the headers for said side wall tubes and the upper and lower headers, respectively, for the front and back wall tubes.

8. In a boiler having a furnace chamber; a cooling screen for the walls of the latter comprising, a lower header disposed along the bottom of one wall; an upper header disposed along the top of the opposite wall; circulating tubes on said walls of said chamber connected into uniformly spaced openings disposed longitudinally of said headers and having portions extending over the roof and floor of said chamber; a steam and water drum disposed parallel to and above said lower header; downcomers connected into uniformly spaced openings disposed longitudinally of said drum and lower header; tubes covering opposite side walls of said chamber; circulator tubes communicating with the upper and lower ends of said side wall tubes and extending across and along the top and bottom, respectively, of said chamber to said upper and lower headers, respectively, said side wall tubes and circulators forming parallel circuits of substantially equal length from said lower header to said upper header; and risers common to all said wall tubes connecting said upper header to said steam and water drum.

9. In a boiler having a furnace chamber; a cooling screen for the walls of the latter comprising; a lower header disposed along the bottom of one wall; an upper header disposed along

the top of the opposite wall; circulating tubes on said walls of said chamber connected into uniformly spaced openings disposed longitudinally of said headers and having portions extending over the roof and floor of said chamber; circulating tubes covering opposite side walls of said chamber; circulators communicating with the ends of said side wall tubes and extending across and along the top and bottom, respectively, of said chamber to said upper and lower headers, respectively, said side wall tubes and circulators forming parallel circuits of substantially equal length between said lower header and said upper

header; a steam and water drum disposed above said headers; downcomers connecting said drum with said lower header for supplying feedwater to said screen tubes; risers connecting said upper header and said drum, said risers resisting the flow of fluid from said headers to said drum to the extent that substantially only steam passes from said header to said drum; and recirculator tubes connecting said headers for returning to said lower header the water separated in said upper header from the steam and water mixture entering said upper header from said wall tubes. 5 10

JULIUS KRUG.
